UNITED STATES PATENT OFFICE.

RUDOLPH S. WEINER, OF EL PASO, TEXAS, ASSIGNOR TO SULLIVAN MACHINERY COMPANY, A CORPORATION OF MASSACHUSETTS.

ROCK-DRILLING TOOL.

Application filed April 10, 1922. Serial No. 551,972.

My invention relates to rock drilling tools or the like.

It has for its object to provide an improved drilling mechanism, and more especially to 5 provide an improved mechanism of the stoper type whereby it is made possible to obtain access to the cleansing fluid supply means readily and quickly. A further object of my invention is to provide an improved stoper 10 of the air or water type wherein it is possible to obtain access to the air or water tubes readily and quickly for purposes of change or inspection.

In the accompanying drawings I have 15 shown for purposes of illustration one embodiment which my invention may assume in practice.

In these drawings,—

Fig. 1 is a view partially in elevation and 20 partially in central longitudinal section through a stoping drill embodying the illustrative form of my invention.

Fig. 2 is a longitudinal central sectional view of the rear end of the motor and front 25 end of the feed mechanism.

Fig. 3 is a section on the line 3—3 of Fig. 2, parts being indicated in a plurality of positions.

In the illustrative construction, it will be 30 noted that I have shown a stoper of generally standard form including a drill motor of any suitable type, herein of the valveless percussive type and including a cylinder 1 having a hammer piston 2 therein, which piston operates through a tappet 3 on a drill steel 4 carried in a suitable chuck 5 on the front end of the motor. As in a usual construction, cleansing fluid supply means 6 extends axially through the piston 2 and into a tappet 3 or 35 drill steel 4 as may be preferred and has its rear end removably connected to the rear head member 7 by suitable mechanism generally indicated by 8 in such manner that the same may be withdrawn from the rear end of the cylinder. The head 7 will be noted to be secured to the cylinder 1 by means of side rods 40 10 and 11 whose description will be amplified as necessary hereafter. Suitably operatively connected to the drill motor, herein to the head 7, is also a feeding mechanism which 45 may be of any desired type and herein includes elements 12 and 13, the former of which is a feed piston and the latter a feed cylinder, this feeding mechanism being adapted, when a foot 14 herein carried on the end 50 of the feed piston 12 is disposed against a support, to feed the drill motor away from the support and toward the work, the feed being controlled through any usual controlling mechanism, herein incorporated in a valve mechanism 15 which also controls the drilling motor.

In the form of my improved construction shown for purposes of illustration, it will be observed that the side rod 10 is provided at 55 opposite ends with nuts 16 and 17 and these ends engage a forward head 18 and the rear head 7 and lock the same to the cylinder 1. It will be observed that the nut 17 is seated in a counterbore 19 in the rear end of the rear 60 head 7 whereby the rear head is provided with a smooth surface throughout its entire extent. The side rod 11 is provided with a nut 20 corresponding to the nut 16 and engaging the front cylinder head 18. This rod 11 at its 65 rear end is provided with a shoulder 21 which takes the place of the nut 17 and engages the rear surface of the head member 7 and clamps the parts together. For the purpose of tightening the side rod 11 and nut 20, various 70 means can be employed, the nut 20 being made suitable for the application of a wrench, instead of as shown, or a square or other polygon shaped extension 22 being formed at the rear end of the side rod 11 to permit the 75 latter to be rotated and thereby draw tight the heads 7 and 18 upon the cylinder member 1. The side rod 11 has an extension of substantially the same size as the main portion thereof at the opposite side, i. e. to the rear of 80 the collar 21 which passes through a bore 23 formed in a plate 24 secured to the front end of the feed cylinder 13. A lock washer 25 and nut 26 draw up the feed cylinder into 85 tight engagement with the rear end of the head 7. A screw 27 extending through the rear head 7 from the forward end thereof enters a threaded socket 28 in the opposite side of the flange 24 and serves to draw the other 90 side of the flange into close engagement with the head 7. Suitable washers may be interposed between the head 7 and the flange 24 if desired, but as the method of this is obvious, they have not been shown.

The mode of operation of this device will be 105 readily understood. When it is desired to change a tube or secure access to the rear end of the drilling motor for any purpose, the screw 27 is unscrewed from its socket 28 in the flange 24, the nut 26 is slightly backed 110

off to permit ease of turning the cylinder 13 about the axis of the side rod 11, and then the screw 27 having been withdrawn, the cylinder is swung laterally about the axis of the side rod 11 as indicated by dotted lines in Fig. 3 and free access is had to the mechanism 8. After the necessary inspection or repairs have been made the parts are swung back to original position, the screw 27 inserted and screwed home and the nut 26 tightened.

While I have in this application, specifically described one embodiment which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a drilling motor comprising a cylinder and heads therefor, side rods maintaining said heads in operative relation to the cylinder, one of said side rods having an extension formed thereon, feeding mechanism for said motor pivotally connected thereto for swinging movement about said side rod extension, and means for locking said feeding mechanism against swinging movement.
2. In combination, a drilling motor comprising a cylinder having heads and side rods holding said heads in assembled relation with respect to said cylinder, one of said side rods being shorter than the other and terminating in front of the rear surface of the rear head, the other of said side rods extending a substantial distance beyond said head, feeding means for said motor, and means for holding said feeding means to said motor including an operative engagement between said longer side rod and said feeding means.
3. In combination, a drilling motor comprising a cylinder and heads therefor held in assembled relation by a pair of side rods, one of said side rods terminating at its rear end in front of the rear surface of the rear head,

the other of said side rods having a shoulder thereon engaging said rear head at the rear side thereof and having a projection to the rear of said shoulder, feeding mechanism pivotally connected to said projection, and means for holding said feeding means in rigid position with respect to said motor.

4. In combination, a drilling motor having a plurality of parts, means under tension for holding the parts thereof in assembled relation, aligned feeding means for said motor normally rigidly connected thereto at the rear end thereof, cleansing means carried by said drilling motor and removable rearwardly therefrom, and means operable to permit said feeding means to be swung laterally relative to said motor about said holding means as a pivot to permit removal of said cleansing means while the tension of said holding means remains the same.

5. In combination, a drilling motor having a plurality of parts, elements acting under tension for holding the parts thereof in assembled relation, feeding means for said motor, means for securing said feeding means to said drilling motor including one of said motor holding elements and a shorter holding element, the connection of said feeding means to one of said elements permitting pivotal movement about the same on release of said other holding element to allow access to the rear end of the motor while the tension on said motor holding elements remain the same.

6. In combination, a drilling motor comprising a plurality of parts, means for holding said parts together including a side rod having a portion thereof under tension, feeding means for said motor, and connecting means between said motor and feeding means including means for pivotally connecting the latter on said side rod wholly outside of the tensioned limits thereof whereby the feeding means may be swung to one side to permit access to the rear end of said motor while the tension of said tensioned portion of the rod remains the same.

In testimony whereof I affix my signature.

RUDOLPH S. WEINER.
